Atty.

UNITED STATES PATENT OFFICE.

AUGIE L. HANSEN, OF EVANSTON, ILLINOIS, ASSIGNOR TO JUSTRITE MANUFACTURING COMPANY, OF CHICAGO, ILLINOIS, A CORPORATION OF ILLINOIS.

RECEPTACLE.

1,274,878.

Specification of Letters Patent. Patented Aug. 6, 1918.

Application filed May 18, 1917. Serial No. 169,446.

To all whom it may concern:

Be it known that I, AUGIE L. HANSEN, a citizen of the United States, and a resident of Evanston, in the county of Cook and State of Illinois, have invented certain new and useful Improvements in Receptacles, of which the following is a specification.

My invention relates to receptacles which may be used for holding various materials, but which are particularly adaptable for miners' use to contain carbid from which the miners' acetylene lamps are from time to time replenished.

One of the important objects of my invention is to provide a cover which will always be held to the receptacle but which can readily be opened by the fingers of the hand which holds the receptacle and to any degree so that pouring of the contents from the receptacle may be readily controlled. Another object of the invention is to permit shifting of the cover into position to lie against one edge of the receptacle so that a number of receptacles can be placed side by side and edge to edge to be simultaneously filled. Another object is to provide improved spring mechanism tending to hold the cover securely to the receptacle but yielding readily to permit opening of the cover or the placing thereof in position for filling of the receptacles.

The above and other features of my invention are embodied in a structure shown on the accompanying drawing, in which drawing

Fig. 1 is a side elevational view with parts broken away,
Fig. 2 is an edge view,

Fig. 3 is a top view with the cover shown in position for filling of the receptacle,

Fig. 4 is a sectional view on plane 4—4, Fig. 3, and

Fig. 5 is a sectional view on plane 5—5. Fig. 4.

The receptacle shown is of rectangular cross-section and of a size to be readily carried in the pocket. The receptacle body is preferably of sheet metal comprising the large sides 10 and 11, the narrow sides 12 and 13, and the bottom 14. The cover structure is also of sheet metal and comprises the flat top 15, and the side and edge flanges 16 and 17 respectively for overhanging the receptacle body sides a distance. Extending downwardly from the opposite sides of the cover top are the plates 18 and 19,

the top flanges and plates being preferably formed from a single piece of sheet metal. Near their lower ends these plates support pins 20 and 21 which extend inwardly through the slots 22 and 23 formed in the sides 10 and 11 respectively. These slots extend diagonally as shown and are of such length that the cover structure may be tilted or swung part-way open, as illustrated by the dotted lines in Fig. 1, to permit pouring of the contents from the receptacle or swung to bring the top 15 alongside of and against the narrow side 13 of the receptacle body as illustrated by the dot-dash lines Fig. 1.

Improved spring mechanism is provided which tends to shift the cover structure from a neutral position into closed position or into fully open position with the cover top against the narrow side 13. Against the inner sides 10 and 11 housings 24 and 25 are secured over the slots 22 and 23 and the pins 20 and 21 projecting through the slots, and in the housings springs 26 and 27 are provided which bear downwardly on the pins to resist shifting of these pins upwardly along the slots. In the housing 25 the structure of the springs is clearly shown, a piece of spring wire being bent intermediate its ends to form one or more spring loops 28, the outer end 29 of the spring extending upwardly through the housing where it may be readily soldered to the receptacle wall, and the other end 30 of the spring engaging with the pin 21 between the wall 11 and the washer or plate 31 secured to the inner end of the pin. In the housing 24 is a similar spring whose outer end 32 extends upwardly through the top of the housing to be soldered in place and whose inner end 33 engages with the top of the pin 20 between the receptacle wall 10 and the washer 34 secured to the inner end of the pin. These springs always press downwardly on the pins and therefore resist upward movement of the plates 18 and 19 and the cover 15 will always be held snugly against the container, either against the top of the container to close it or against the side 13. When the cover 15 is held in a neutral position against the upper edge of the side 13 the springs will hold it in such position, but when shifted to either side of this neutral position it will be thrown by the springs either to closing position or to position against the side 13. To enable the cover structure to be readily swung when the receptacle is held in the

hand, sections 35 and 36 are deflected outwardly from the front edges of the plates 18 and 19 to form finger engaging abutments just below the cover top 15. Then, 5 when the receptacle is held with the palm of the hand and fingers around the side 13, one of the abutments can be engaged by the thumb and the cover structure readily swung and held open to any desired degree 10 while the contents are being poured from the receptacle. Thus the flow of the contents from the receptacle can be readily controlled and immediately upon release, the cover structure will be thrown by the springs 15 to reclose the receptacle. The housings 24 and 25 may be entirely closed or may be left open at their lower ends so that any of the contents which enter during the pouring process will fall when the receptacle is again 20 moved to upright position. The plates 18 and 19 are sufficiently extended so that the slots 22 and 23 will always be closed thereby.

When the cover structure is swung to 25 bring its top 15 alongside of the receptacle side 13 between the upper and lower edges thereof, any number of receptacles can be placed side by side or edge to edge within a large box or hopper and then a considerable 30 quantity of material poured thereover to fill each receptacle with the desired quantity, this being the usual practice in mines when the receptacles are to be filled.

I thus produce a strong, inexpensive receptacle which can be used for any material, 35 but which is particularly adaptable for mine use where it is usually carried in the pocket by the miner and subjected to heavy use. The particular construction and application 40 of the cover structure prevents breaking or detachment thereof from the receptacle body and when the receptacle is held either in the left or right hand the cover structure can be readily manipulated while the 45 contents are being poured.

I do not of course desire to be limited to the precise construction and arrangement shown and described as modifications are no doubt possible which would still come within 50 the scope of the invention.

I claim as follows:

1. In a receptacle, the combination with a rectangular body part having an opening at its upper end, of a cover structure comprising 55 a top plate and side plates extending therefrom alongside of the opposite sides of said body part, diagonal slots in said opposite sides, pins extending from said side plates through said slots into the interior of 60 the body part, V-shaped wire springs anchored at one end to said body part and having their other ends engaging said pins, said pin and slot connection permitting said

cover structure to be swung to bring its top plate into various positions with reference 65 to said opening and said springs resisting such swing.

2. In a receptacle, the combination with a rectangular body part having an opening at its upper end, of a cover structure comprising 70 a top plate and side plates extending therefrom alongside of the opposite sides of said body part, diagonal slots in said opposite sides, pins extending from said side plates through said slots into the interior of 75 the body part, and flat springs formed by bending lengths of wire into V-shape with loops at the apexes, said springs being anchored at one end inside the body against the opposite sides thereof, the other ends of 80 said springs pressing downwardly on said pins, said pin and slot connections permitting bodily swing of said cover structure and said springs resisting such swing.

3. In a receptacle, the combination with a 85 rectangular body part having an opening at its upper end, of a cover structure comprising 90 a top plate and side plates extending therefrom alongside of the opposite sides of said body part, diagonal slots in said opposite sides, pins extending from said side plates through said slots into the interior of 95 the body part, flat springs formed by bending lengths of wire into V-shape with loops at the apexes, said springs being anchored 100 at one end inside the body against the opposite sides thereof, the other ends of said springs pressing downwardly on said pins, and washers secured to the inner ends of said pins to hold the spring ends thereto, said pin 105 and slot connections permitting swing of said cover structure and said springs resisting such swing.

4. In a receptacle, the combination with a rectangular body part having an opening at 110 its upper end, of a cover structure comprising a top plate and side plates extending therefrom alongside of the opposite sides of 115 said body part, diagonal slots in said opposite sides, pins extending from said side plates through said slots into the interior of the body part, V-shaped wire springs anchored at one end to said body part and having their other ends engaging said pins, said pin and slot connection permitting said 120 cover structure to be swung to bring its top plate into various positions with reference to said opening and said springs resisting such swing, and protecting housings within the body part secured against the opposite sides thereof to cover said springs, slots and pins.

In witness whereof I hereunto subscribe my name this 14th day of May, A. D. 1917.

AUGIE L. HANSEN.
